DESIGN FOR A COMBINED BOTTLE AND HOLDER

Charles H. Burger, New York, N.Y., assignor to
Dermetics, Inc., New York, N.Y.

Application April 5, 1946, Serial No. 128,470

Term of patent 14 years

(Cl. D58—26)

To all whom it may concern:

Be it known that I, Charles H. Burger, a citizen of the United States, residing at New York, in the county of Bronx and State of New York, have invented a new, original, and ornamental Design for a Combined Bottle and Holder, of which the following is a specification, reference being had to the accompanying drawing, forming part thereof, wherein—

Fig. 1 is a side elevational view of the combined bottle and holder in nested relation;

Fig. 2 is a top plan view of the article of Fig. 1;

Fig. 3 is a side elevational view of the bottle and holder of Fig. 1 shown separated; and

Fig. 4 is an end view as seen in Fig. 3 of the combined bottle and holder showing my new design.

I claim:

The ornamental design for a combined bottle and holder, as shown.

CHARLES H. BURGER.
